A detailed cross-sectional technical drawing of a mechanical device. At the top, a cylindrical component labeled '11' is shown. Below it, a central gear labeled '37' is mounted on a shaft. The housing of the device is labeled '11' on the left and '20' on the right. A base or support structure is labeled '21'. A callout labeled '33' points to a circular feature on the left side. Another callout labeled '35' points to a circular feature on the left side, below '33'. A callout labeled 'IV' is located at the bottom center. The drawing uses fine lines and cross-hatching to indicate depth and material.

HEATING SYSTEM

Horace S. Kehm and Courtland G. Newton,
Chicago, Ill.; said Newton assignor to said
Kehm

Application May 22, 1939, Serial No. 275,044

9 Claims. (Cl. 237—59)

The present invention relates in general to a heating system and is particularly concerned with improvements in heating systems of the type wherein forced flow circulation of hot water is utilized for the transference of heat energy from a boiler to remotely located radiating means, and further contemplates novel means for improving the efficiency and operation of such systems.

In the Horace S. Kehm Patent No. 2,020,064, a heating system is illustrated and described, wherein heated water is circulated under pressure from a boiler through a single pipe main in the form of a loop to which a plurality of radiators are connected by supply and return risers respectively. At each radiator, the main constitutes a shunt or by-pass for the radiator, and the fittings by which the supply and return risers are connected to the main are so arranged that stratified flow of the water results in the main.

More specifically, during flow of water in the main between the radiators, the hot water bypassing a radiator will be delivered at the radiator return connection to the top portion of the main, and the somewhat cooled water returning from the radiator will be delivered to the bottom portion of the main. At the supply risers of the radiators, the connection fittings are arranged to take water from the upper portion of the main, the water at the lower portion of the main flowing through the radiator by-passes.

The system described in the aforementioned patent is very suitable and efficient in operation when utilized in relatively large heating systems in which the main loop is of relatively large diameter pipe. In small systems, however, such as would be installed in a small home and would usually contain eight or less radiators, the economical size of the main loop becomes so small that the advantages resulting from stratified flow of the water are lost or reduced to such an extent that the stratification of the water becomes impracticable.

Having in mind the unapplicability of a stratified system of flow for economic low cost installation of small heating systems, the present invention contemplates an improved arrangement wherein efficient heating may be secured in a small single main loop heating system having a comparatively few radiators and a main line of relatively small diameter.

A further object of the present invention is to provide an improved heating system wherein all the radiators may be furnished of the same standard size irrespective of the sizes of the rooms in which they may be installed, thus elimi-

nating the cost of skilled engineering service for calculating and determining the various radiator sizes to meet different installation conditions.

Another object of the herein described invention is to provide an improved single loop heating system in which the amounts of flow of heating fluid through the radiators may be successively graduated and increased as the temperature of the heated fluid is successively decreased by flow through the radiators.

Still another object is to provide a looped main heating system having flow choking means at each radiator for controlling flow therethrough, and arranged to open whenever the fluid pressure in the main exceeds a predetermined amount.

Yet another object of the invention is to provide an improved fitting for connecting a radiator into the main of a loop type heating system, this fitting embodying an adjustable spring biased baffle for choking flow through the fitting but operating upon predetermined increase of pressure in the heating system to move to ineffective position and thus relieve the system pressure and permit circulation through the system.

In accordance with the general features of the herein described system, it is proposed to provide a single pipe main in the form of a loop to which the radiators are connected by supply and return risers. This loop is connected to a suit-

able furnace or device for heating the fluid, and the heated fluid is circulated under pressure by means of a suitable circulating pump. The supply risers of the radiators are connected into the main loop by means of the usual T-pipe fitting, and the radiators at their outlet are provided with the usual throttling valve. The return risers of the respective radiators are each connected to the main by means of a special T-fitting.

This special fitting, which is more fully described subsequently, is arranged with an adjustable baffle which serves as a choke or retarder for the water in the main which is by-passed around each radiator. These baffles are arranged with adjusting handles which are exteriorly of the fitting body so that the baffle may be adjusted to provide more or less choking or retarding effect as desired.

Since the conditioned fluid in this type of system is successively shunted through the radiators from the main loop the successive baffles or retarders may be successively closed by greater amounts so that as the conditioned fluid is gradually cooled by passing through radiators, the subsequent radiators will pass more fluid so

that the heating capacity of all the radiators will be substantially equalized. Since the last radiator of the series will have its baffle almost fully closed, it will be apparent that if this radiator should be shut off by its throttling valve, circulation through the preceding radiators would be seriously affected and pressure would build up ahead of the last baffle.

As an additional feature, this baffle is arranged to be normally biased by a spring, so that when the pressure builds up ahead of it, the baffle will be opened independently of its adjusted position and relieve the pressure so that the circulation through the system may be continued efficiently.

Other objects and features of the invention will more readily appear from the following detailed description taken in connection with the accompanying drawing which illustrates a single embodiment thereof, and in which:

Figure 1 is a view illustrating a single main loop heating system embodying the features of the present invention;

Figure 2 is an enlarged fragmentary portion of the system showing in elevation a pipe connection fitting having an adjustable baffle or flow retarder, such as utilized in the system of the present invention;

Figure 3 is a longitudinal section taken through the same to show its internal construction; and

Figure 4 is a transverse sectional view taken through the fitting substantially on line IV—IV of Figure 2.

As shown on the drawing:

In the illustrated embodiment of the present invention there is shown in Figure 1 a boiler 10, which is connected at its outlet to one end of a single pipe main loop 11 and its inlet to the other end of the main loop. Interposed in the main loop is a suitable circulating pump 12 by means of which conditioned fluid may be circulated through the system, in this instance water which has been heated in the boiler.

A plurality of heat exchange devices, in this instance radiators as shown at 13, 14, and 15, are successively connected to the main line by means of supply and return risers 16 and 17. It will be noted that connection of the supply riser is made to the main line by means of an ordinary T-fitting as shown at 18 and that each radiator at its connection with the return riser is provided with a suitable control or throttling valve 19 by means of which the circulation of conditioned fluid through the radiator may be manually controlled.

Each return riser 17 is connected with the main line by means of a T-fitting 20 having a construction which will be subsequently described in detail. In the disclosed arrangement, it will be noted that the main line at each radiator in its portion lying between the fittings 18 and 20 forms a shunt flow circuit past the radiator.

In general, the fittings 20 are so arranged as to retard or choke the flow of fluid through the associated shunting portions of the main line, and this choking characteristic is made adjustable so that the amount of fluid forced through the associated radiator may be adjusted.

More specifically, the fitting 20 comprises a T-shaped body structure 21, as shown in Figures 2, 3, and 4, this body being constructed of any suitable material such as wrought iron, brass, and the like. The body structure defines an interior chamber 22 of substantially rectangular cross section. This chamber communicates with a pair of main line connection openings 23 and

24, and also a branch connection opening 25 which may be angularly disposed with reference to the main line connection openings. These openings, if desired, may be internally threaded for pipe connection.

Within the chamber 22, there is disposed adjacent the main opening, which will be utilized for the inlet of fluid to the fitting, a baffle plate 26 having its uppermost edge margin provided with a barrel portion 27. The barrel 27 is rotatably mounted upon a transversely extending shaft or pivot pin 28 supported in the body structure for rotative movements, one end of this pin being disposed in a projecting portion 29 of the housing, and the other end being extended through an integrally formed tubular boss 30 on the opposite side of the body structure. Intermediate its ends, the boss 30 is provided with an internal shoulder 31 which forms an abutment seat for a washer 32 surrounding the shaft and serving to maintain it at the axis of the tubular boss. The outer end of the boss is threaded for threadedly receiving a cap member 33 which cooperates with the washer 32 in maintaining a suitable packing 34 compressed around the associated end of the pivot member 28 and thus prevent leakage of fluid from the fitting body along the pivot member.

The end of the pivot member which projects through the cap 33 is provided with a crank handle 35 by means of which the pivot member 28 may be rotated from the exterior of the fitting body.

Arrangement is made for maintaining the crank handle in any position of adjustment by providing a detent spring 36 having one end secured to the handle, and its other overlying and riding upon a curved rack 37 on the fitting body. This rack may be formed as a separate element and secured to the body or, if preferred, may be integrally formed on the body during its construction.

As shown in Figure 4, the right hand end of the barrel 27 is provided with a semi-circumferential end slot 38 in which there is disposed a pin 39 projecting from this end of the pivot member.

At the left end of the barrel 27, between this end of the barrel and the washer 32, there is provided a coil spring 40 which surrounds the pivot member. One end of this spring is anchored as at 41 to the shaft, while the other end of this spring is deflected so as to extend over and resiliently engage the innermost surface of the baffle 26 and normally move it in a clockwise direction as viewed in Figure 3, until this movement is stopped by the abutment of pin 39 against one end of the end slot 38.

With the foregoing construction, it will be apparent that the baffle plate 26 may be swung by means of the handle 35 to a position, as shown in Figure 3, wherein it fully closes the opening 23 of the fitting and engages an abutment stop projection 42 at the bottom of the fitting, or the plate may be moved through an opening direction with reference to the opening 23 to a limiting position, as shown in dotted lines, in which the branch opening 25 will be fully closed or cut off from the chamber 22 within the fitting.

During the adjusting movement, the spring 40 is carried along with the rotational movement of the pivot pin 28. However, if pressure is applied against the outer surface of the baffle plate 26, the baffle plate may be independently swung on the pivot 28 against the pressure of spring 40,

and thus automatically act as a relief valve with reference to the inlet opening 23.

Since the fittings 20 are all similarly constructed, they may be indiscriminately utilized for connecting the return risers from the radiators to the main line without consideration as to whether the radiator is the first radiator of the system or one of the subsequent radiators.

As shown in Figure 1, it will be noted from the adjusted position of the handle 35 of the respective fittings 20, that the baffle 26 for the radiator 13 would be in substantially opened position, that the baffle 26 associated with the radiator 14 is somewhat further closed, and that the last baffle would be almost fully closed with reference to the main line of the system. Thus, as the conditioned fluid or heated water in this instance is circulated through the main line, the respective baffles operate to successively cause more fluid to be circulated through the associated radiators as the conditioned fluid becomes cooled.

Due to the fact that the baffle 26 associated with the last radiator of the system, in this case radiator 15, is almost fully closed, it will become apparent that should this radiator be shut off by closing its valve 19, all the water flowing through the main line must pass through the opening determined by the position of the baffle 26. Since this baffle is almost fully closed, it is apparent that circulation of fluid in the main line would be seriously interfered with, and it would not be possible to efficiently operate the preceding radiators 13 and 14. However, this difficulty is automatically taken care of due to the relief feature of the fitting. That is, pressure will build up in the main line ahead of the baffle 26 associated with the radiator 15, and when this pressure reaches a predetermined amount sufficient to move the baffle against the spring 40, the baffle will be swung in a counter-clockwise direction, as previously explained, on the pivot pin 28, and thus permit circulation of fluid through the system without passing through the radiator which is shut off.

Although the baffles of the fittings 20 will in general be adjusted in the manner described above for successively determining the flow through the radiators accordingly as the temperature of the conditioning fluid is modified, the baffle and relief arrangement therefore have further advantages in that it enables independent adjustment of the baffles of the radiators in the system to compensate for the different resistances of the flow paths through the radiators and their connections.

Such differences in the resistance to flow through the radiators may arise from a number of causes. For example, the supply and return connections for one radiator may be of a different length than those of another radiator, or it may not be possible to utilize the theoretically proper size of pipe for the different radiators due to the standardization of pipe sizes.

Thus it will appear that not only is there a possibility of the last radiator of the system having its baffle substantially closed, but other radiators ahead of the last one might also under certain conditions have a considerable closure. Irrespective of which baffles may be substantially closed, these baffles will be relieved whenever the pressure builds up ahead of them to a predetermined amount, as might happen when their associated radiators are shut off. Ample system

circulation will therefore always be assured for the radiators remaining in operation.

While we have chosen to describe the present invention in connection with a heating system, we do not wish to be limited to such specific use, as it will readily be appreciated that the invention is susceptible of other uses and may be utilized advantageously, for example, in a cooling system.

From the foregoing description, it will be apparent that the present invention provides an improved heating system of the single main loop type which is particularly adapted for economic installation where low cost is a factor as in small heating systems for homes and the like; which enables the installation of radiators of the same standard size irrespective of the heating requirements of the rooms in which the radiators are to be installed and without the necessity of the services of a skilled engineer to calculate various radiator sizes to meet the different installation conditions; which provides a system in which the amount of flow of heating fluid through the radiators may be successively graduated to provide increased flow as the temperature of the heated fluid diminishes; which is so arranged as to provide for relief operation whenever a radiator is shut off and the associated baffle or retarder is in such position as to prevent proper flow in the main line to efficiently operate the remaining radiators; and which includes an improved fitting for connecting the return risers of the various radiators to the main line, this fitting embodying an adjustable retarder for determining the circulation through the radiators with which the respective fittings are associated.

Now, it is of course to be understood that although we have described in detail the preferred embodiment of our invention, the invention is not to be thus limited, but only insofar as defined by the scope and spirit of the appended claims.

We claim as our invention:

1. In a system of the character described, a main flow line for a fluid under pressure, a heat exchange device having inlet and outlet connections with said line, and yieldable baffle means normally adjustable to control the fluid flow in the portion of the main line between said connections, said baffle means being automatically movable to inoperative position relative to said portion of the main line, when the pressure of said fluid is increased above a predetermined amount.

2. In a system of the character described, a main flow line for a fluid under pressure, a heat exchange device having inlet and outlet connections with said line, an adjustable baffle for normally choking fluid flow through the portion of the main line between said connections and determining the amount of fluid circulated through the heat exchange device, and yielding means retaining the baffle in normal adjusted position but enabling movement thereof to an ineffective position relative to said portion of the main line, when circulation of fluid through the heat exchange device is decreased to such an extent as to result in the building up of fluid pressure in the main line above a predetermined value.

3. In a system of the character described, a main flow line for conditioned fluid under pressure, a heat exchanger having supply and return connections with said line, a baffle at the return connection of the heat exchanger with the main line, said baffle being normally adjust-

able to variably impede the fluid flowing through the portion of the main line between said connections, an auxiliary control valve in one of said heat exchanger connections, and pressure responsive means for releasing said baffle relative to its normal adjustment upon increased pressure in the main line due to the closing of said valve.

4. In a heating system, a main flow line for conditioned fluid under pressure, a plurality of radiators each having supply and return connections with said main flow line, movably mounted flow retarder means at each radiator for opposing flow of fluid in the main line between its supply and return connections, said retarder means having increasing effectiveness in the direction of flow of fluid in the main line, whereby the amounts of fluid circulated in said radiators are successively increased as the fluid temperature decreases, and yielding means normally opposing movement of each retarder means to a non-retarding position, whereby at least the most effective of said retarder means may be rendered inactive, when its associated radiator is "shut off", and the remaining radiators operated without decreased flow.

5. In a heating system, a main fluid flow line, a radiator having a fluid supply connection and a fluid return connection with said line, said latter connection including a T-fitting having internal adjustable baffle means normally opposing fluid flow in the main line, and pressure responsive means for rendering said baffle means ineffective to oppose said fluid flow upon predetermined fluid pressure in the main line.

6. In a system of the character described, a main flow line for conditioned fluid under pressure, a heat exchanger having supply and return connections with said line, a baffle at one of said connections of the heat exchanger with the main line, said baffle being normally adjustable to variably impede the fluid flowing through the portion of the main line between said connections, an auxiliary control valve in one of said heat exchanger connections, and pressure responsive means for releasing said baffle relative to its

normal adjustment upon increased pressure in the main line due to the closing of said valve.

7. In a heating system, a main fluid flow line, a radiator having a fluid supply connection and a fluid return connection with said line, one of said connections including a T-fitting having internal adjustable baffle means normally opposing fluid flow in the main line, and pressure responsive means for rendering said baffle means ineffective to oppose said fluid flow upon predetermined fluid pressure in the main line.

8. In a system of the character described, a main flow line for conditioned fluid under pressure, a heat exchanger having supply and return connections with said line, pressure relief means responsive to the pressure of said fluid in the main flow line, said means including a movable resiliently mounted baffle at the return connection of the heat exchanger with the main line, said baffle being adjustable to variably impede the fluid flow through the portion of the main line between said connections, whereby the amount of fluid passing through the heat exchanger is determined, and said baffle being movable to relief position by the action of abnormal main line pressure to enable substantially unimpeded fluid flow through said main line portion.

9. In a heating system, a plurality of radiators having inlet and outlet connections respectively to a fluid supply and fluid return, a shunt bypass between said connections of each radiator, adjustable retarder means in each radiator connection for opposing fluid flow through its bypass and determining the amount of fluid circulating through the radiator, means supporting said retarder means in said radiator connection for movement independently of its adjustment to a position in non-opposing relation to flow through the by-pass by the fluid pressure acting thereon, and resilient means cooperating with said supporting means for opposing said movement at normal pressures but enabling said movement at a predetermined increased pressure.
